THOMAS BULLIVANT, OF LONDON, ENGLAND.

Letters Patent No. 75,853, dated March 24, 1868.

IMPROVED METHOD OF HANGING WINDOW-SASHES.

The Schedule referred to in these Letters Patent and making part of the same.

TO ALL WHOM IT MAY CONCERN:

Be it known that I, THOMAS BULLIVANT, of London, England, have invented a new and useful Improvement in Hanging Balanced Window-Sashes and Roller Window-Blinds or Sashes; and I do hereby declare that the following is a full, clear, and exact description thereof, which will enable those skilled in the art to make and use the same, reference being had to the accompanying drawings, forming part of this specification.

This invention relates to a new and improved mode of hanging balanced window-sashes, whereby the latter may be taken from the window-frame with the greatest facility, for the purpose of cleaning, glazing, painting, &c., and the sashes also fitted in the window-frame without any difficulty whatever. In the accompanying sheet of drawings—

Figure 1 is a face view of a window, partly in section, and provided with my improvement.

Figure 2, a vertical section of the same, taken in the line *z z*, fig. 1.

Similar letters of reference indicate corresponding parts.

A represents a window-frame, which is constructed in substantially the same manner as those now generally made for balanced or adjusted sashes. B B represent the sashes, and C the weights, the cords D of the latter passing over pulleys, E, in the upper part of the frame, and having the weights C fitted in boxes, F, at one side of the frame, as shown in fig. 1. The cords D are not attached directly to the sashes but to metal plates G, as shown clearly in fig. 1. These plates G are fitted in grooves *a* in the ends of the sashes, the upper ends of the plates provided with hooks *b* to catch into holes *c* in metal plates *d* on the tops of the sashes, and the lower ends of the plates provided with upright lips *e* to catch into holes *f* in plates *g*, secured to the inner sides and lower parts of the grooves *a*. The plates G, when thus fitted in the grooves *a*, are secured in position by screws *h*, which pass directly into the sashes, and through holes *a* in the plates made for them, the plates when thus secured extending out from the ends of the sashes sufficiently far to fit into grooves *i* in the inner sides of the jamb-pieces *j* of the window-frame, and serve as guides for the sashes as the same are raised and lowered. This will be fully understood by referring to fig. 1.

In case it is desired to remove the sash from the frame A, the screws *h* of each plate G are removed, the plates G shoved down, so that the hooks *b* will be out of and below the holes *c* in the plates *d*, and the lips *e* out of and below the holes *f* in the plates *g*, and the plates G are pressed inward, so that their outer edges will be flush with the outer edges of the sashes, the plates being secured in this position by re-inserting the screws *h*, which pass through a hole, *k*, made in the plates G for them, as shown in fig. 1.

When the plates G are thus adjusted, the sashes may be removed from the window-frame, and the glass cleaned, or the sashes glazed or painted without any difficulty whatever, and the sashes may be refitted in the frames with the greatest facility, all that is required to effect this, being the removal of the screws *h*, and the adjusting outward of the plates G to the position previously described, and the inserting of the screws *h* through the holes *a*.

I claim as new, and desire to secure by Letters Patent—

The method of attachment of the weight-cords D to the sashes, through the medium of the adjustable plates G, constructed, arranged, and applied in the manner shown, so as to admit of being adjusted to serve as guides for the sashes, and also to admit of the sashes being readily removed from the window-frame when desired.

The above specification of my invention signed by me, this 23d day of August, 1867.

THOMAS BULLIVANT.
